[57] CLAIM

The ornamental design for an evacuator tip, as shown
and described.

DESCRIPTION

FIG. 1 is a view in perspective of the evacuator tip
showing my new design;

FIG. 2 is a side view of the evacuator tip of FIG. 1;

FIG. 3 is a view of one end of the evacuator tip of FIG.
1; and

FIG. 4 is a view of the other end of the evacuator tip of
FIG. 1.
